UNITED STATES PATENT OFFICE.

THOMAS E. WRAIGHT, OF SPRINGFIELD, OHIO, ASSIGNOR OF ONE-HALF OF HIS RIGHT TO A. T. BYERS, OF SAME PLACE.

DASH-MOLDING.

SPECIFICATION forming part of Letters Patent No. 224,317, dated February 10, 1880.

Application filed October 6, 1879.

To all whom it may concern:

Be it known that I, THOMAS E. WRAIGHT, of the city of Springfield, in the county of Clarke and State of Ohio, have invented certain new and useful Improvements in Dash-Moldings, of which the following is a clear, full, and exact specification.

My invention relates to the open tubular molding used for the top finish of dash-boards; and it consists in a peculiar formation of a portion of the slot, whereby the outer ends of the rails or molding-sections are more effectually prevented from being displaced and torn from their fastenings; also, of a device for securing the connection of the two sections of molding at the middle of the dash-board in a firm substantial manner, and at the same time allowing said sections to be detached for repairs or otherwise when said device, covering their joined ends, is loosened for that purpose.

Heretofore the plain tubular molding used for dash-boards, having an open slot its entire length on one side, has been made with said slot of uniform width throughout, so that the compression upon the edges of the face-leathers was alike the whole length of the molding; but my object is to form this slot narrower at the exposed ends for about one and a half or two inches, (from line *d* to the outer end, as shown in Figure 1 and in the view of the under side of the rail-section *a*, Fig. 2,) for the purpose of causing that part of it to compress the face-leathers very tightly when driven on, as it is with a wooden mallet, the outside end of the molding being closed before it is placed upon the dash.

To adapt my molding to the above purpose it is made in two sections, *a a*, and driven on from each end of the dash.

Where the sections connect at the center a clip, *b*, is slipped over the union. This may be made of spring-steel, or it may be made of the same material as the rail, and its lower edges extended down below the rail sufficiently to allow room for the small screw-bolts *c* to be inserted through it and the intervening leathers of the dash, as shown in Fig. 1.

A small plate, *c'*, may be placed on one side below the line of the lower edge of the molding, into which the threaded ends of the screws *c* can enter. This will give a better finish to the clip, the edges of which can also be chamfered to make the molding as smooth and even as possible at this part.

When the molding-sections *a a* are driven 55 on the dash *A* and the clip *b* tightened down upon their connecting ends, as seen in Fig. 1, they cannot be withdrawn endwise, nor can the outer end get loose and slip off, as a molding having a slot of uniform width only frequently does, when the screw or nail usually inserted in its end gets out. This latter circumstance is common after much use.

In Fig. 2, *a'* shows the ordinary width of slot, and *b'* the narrow part used to compress 65 the edges of the leathers near the end. Fig. 3 shows an end view of the clip *b* and the relative positions of the nut-plate *c'* and bolt *c*.

I am aware that dash-moldings have been made in two parts, and the same have been 70 put together and permanently fastened with solder, or otherwise secured; but I do not claim this mode of securing the connecting ends of the sections, as the purpose of detaching the same for replating or repairs would be 75 frustrated by such soldering.

I therefore claim as my improvement—

1. A sectional molding, *a*, having that part of its slot *b'* at the outer end thereof made narrower for the purpose of compressing the 80 edges of the face-leathers more tightly at this point, as hereinbefore specified.

2. In combination with the molding-sections *a a* and the face-leathers of the dash-board *A*, the clip *b*, having bolts *c* and nut-plate *c'*, as 85 and for the purpose set forth.

3. A detachable clip for covering the connection of molding-sections in a dash-board, as and for the purpose specified.

THOMAS E. WRAIGHT.
